UNITED STATES PATENT OFFICE.

JAMES MEADE, OF STOUGHTON, MASSACHUSETTS.

METHOD OF PRODUCING DOUBLED FABRICS.

1,199,400.

Specification of Letters Patent. Patented Sept. 26, 1916.

Application filed November 16, 1915. Serial No. 61,833.

To all whom it may concern:

Be it known that I, JAMES MEADE, a citizen of the United States, residing at Stoughton, in the county of Norfolk and State of Massachusetts, have invented a new and useful Method of Producing Doubled Fabrics, of which the following is a specification.

In the manufacture of doubled fabrics, or those consisting of two layers of material joined by an intermediate layer or layers of a waterproof substance, it has been found very difficult to produce satisfactory goods when one of the layers of fabric is thin or loosely woven, as is the case with mo-
hairs employed for automobile tops. Under the usual method of procedure the back and face layers of fabric are separately coated, partly allowed to dry, and then the two coated surfaces are forced together. The pressure necessary to effect proper adhesion is so great that the coating is often squeezed through the interstices of the thinner fabric and appears upon the face. If this does not occur, the pressure mats down the surface of the face fabric and destroys the original mill-finish, considerably decreasing the value of the goods. The present invention brings about the junction of the layers by a readily pursued method without injuring the appearance of the product.

The accompanying drawing shows dia- grammatically a single form of apparatus by which my improved method may be carried out.

At 10 appears a supply-roll mounted at one extremity of a suitable frame-work 11 and carrying the fabric F which is to furnish one layer of the doubled goods. From the supply-roll the fabric passes over the bed-roll 12 of a spreader S, said bed-roll being driven at the desired speed from any suitable source of power. The preferably adjustable gage-knife 13 of the spreader co-operates with the coating substance indi- cated at M to distribute a thin coat over the upper face of the fabric. Upon leaving the spreader the now coated fabric is directed by a driven roll 14 about a heating coil 15, and then travels down about idler rolls 16 and again upwardly to the driven bed-roll 17 of a second spreader S'. The gage-knife 18 of the spreader S' applies to the coated surface of the fabric F a thin film of a quite fluid and highly adhesive substance M', say

one containing a considerable amount of rubber. The thickness of this coating may be determined by the adjustment of the gage-knife 18. Beyond the spreader S' in the direction of advance of the material are standards 19, in which are mounted vertically adjustable supports 20 carrying the bearing blocks 26 of a pressure-roll 27. These blocks are adjustable longitudinally of the supports, and therefore the roll 27 is movable toward and from the bed-roll 17 as well as vertically.

The fabric F, with its set or hardened coating applied at the spreader S and its just applied and undried coating given by the spreader S', travels under the roll 27 and over a guide-roll 28 which is located quite close to the bed-roll 17 and in the same horizontal plane. From a supply-roll 29 the face-fabric F' passes over and then beneath the pressure-roll 27, which forces the two layers of fabric together, though with a relatively light and yielding pressure. The peculiar action of this pressure-roll is due to the fact that there is no co-operating pressure member beneath the goods, the roll 27 acting upon the run between rolls 17 and 28, so that the goods are free to move from the source of pressure, held against the roll 27 only by their own tension. This roll is adjusted as closely as possible to the bed-roll 17, yet permitting the desired yield of the goods, and therefore the coating of the substance M' comes into contact with the face fabric F' before it perceptibly dries and in a fluid and highly adhesive condition. This being the case, the light pressure of the roll 27 effectively smears and distributes it between the entire meeting surfaces of fabric and secures the proper adhesion. So thin is the film of the substance M' and so delicate the pressure, that there is no danger of its passing through the fabric, and the surface fibers are not matted down, either by the adhesive or by the pressure. In this way the retention of the natural or mill-finish is assured.

From the roll 28 the doubled goods travel beneath and about a considerable portion of the periphery of a large driven heating drum 30, being held thereto at the delivery end of the machine by a guide-roll 31. This sets the coating of the substance M' and completes the goods, which are received by

the winding roll 32, so rotated as to keep the material under proper tension.

I claim as my invention:

1. The method of producing doubled fabrics which consists in applying to a layer of fabric an extremely thin coating of a highly adhesive material, immediately after such application bringing into contact with the adhesive coating a second layer of fabric, and pressing the two layers together while they are movable from the source of pressure.
2. The method of producing doubled fabrics which consists in applying to a layer

of fabric a coating of water-proof material, 15 drying said coating, applying to such coating a film of highly adhesive material, immediately thereafter and before the adhesive perceptibly dries bringing into contact with the adhesive a second layer of fabric, 20 and pressing the two layers lightly together while they are movable from the source of pressure.

Signed at Stoughton, in the county of Norfolk and State of Massachusetts, this 25 twelfth day of November, 1915.

JAMES MEADE.
